PORTABLE DRILLING RIG

Charles A. Hirschberg, Mountain Lakes, N. J.,
assignor to Worthington Pump and Machinery
Corporation, New York, N. Y., a corporation of
Virginia

Application February 4, 1937, Serial No. 124,093

14 Claims. (Cl. 255—51)

This invention relates to portable drilling rigs particularly designed for use in connection with percussive drills such as rock drills or the like, and the primary object of the invention is to provide a rig which is mobile and may be moved from place to place with comparative ease and one which will permit of a wide range of settings of a drill to meet conditions of drilling as they arise.

10 In quarrying of rock, in grading for highway construction, in excavating, and in many other instances where drilling and blasting of rock is required, it has been the practice where the use of drills too large to be hand-held is necessary, to set up what is commonly called drill columns for supporting the drills during operation; however, these columns must be taken apart and carried from one position to another, assembled and set up for each series of holes drilled. This requires considerable labor and time and is costly, and also the number of adjustments of a drill on such a column is limited within a relatively narrow range.

Recently the art has embodied portable drilling rigs or apparatus with various degrees of mobility and adjustability of drills, such as those known as wagon drills, and others lighter in weight and more mobile having comparatively wide ranges of adjustment, which overcome the disadvantages of the column mountings. Such rigs are designed however for use in relatively open and unrestricted spaces and are not adaptable for use in places where it is necessary to drill holes close to a wall or in other relatively confined places.

It is an object of the present invention to provide a portable drilling rig which embodies all of the advantages of drilling rigs as above referred to and includes many other advantages and structural improvements which materially broaden its scope of operation and further reduce the labor and time required in setting the drill carried thereby.

With these and other objects in view, as may appear from the accompanying specification, the invention consists of various features of construction and combination of parts, which will be first described in connection with the accompanying drawings, showing a portable drilling rig of the preferred form embodying the invention, and the features forming the invention will be specifically pointed out in the claims.

In the drawings:

Fig. 1 is a side elevation of the improved portable drilling rig.

Fig. 2 is a top plan of the improved portable drilling rig with the drill-carrying members and the drill removed.

Fig. 3 is a side elevation of the improved drilling rig with the drill removed. 5

Fig. 4 is a fragmentary vertical section taken on the line 4—4 of Fig. 3.

Fig. 5 is a detail cross section through one part of the drill-carrying member.

Fig. 6 is a longitudinal section, with parts 10 broken away, taken on the line 6—6 of Fig. 5.

Fig. 7 is a detail cross section through a part of the drilling rig taken approximately on the line 7—7 of Fig. 3.

Fig. 8 is a detail section taken on the line 8—8 15 of Fig. 3.

Fig. 9 is a plan view of a modified form of the part of the drill-carrying member.

Fig. 10 is a cross section on the line 10—10 of Fig. 9. 20

Figs. 11 to 18 inclusive, are diagrammatic views of the drilling rig showing it in various phases of adjustment and illustrating some of the many positions and/or adjustments of the positions of a rock drill which it is possible to obtain by the 25 present portable drilling rig.

Referring more particularly to the drawings, the improved portable drilling rig comprises a carrying frame 1, which is shown in Figure 2 of the drawings as substantially U-shaped in plan 30 with one end open.

The U-shaped carrying frame 1 has wheels 2 and 3 connected to the ends of the legs or side members 4 of the frame, and a third wheel 5 swivelly connected by means of a suitable bracket 35 6 to the center of the cross member 7 thereof. The wheels 2 and 3 are adjustably connected by means of swinging arms 8 to the ends of the side members 4 and they are held in adjusted position by means of locking pins 9 and segments 10. 40 Thus the wheels 2 and 3 may be positioned with their axes parallel to the side members 4 as clearly shown in Figure 2 of the drawings, or they may be swung at right angles thereto, with their axes extending transversely of the side members 4, depending upon the particular use to which the drilling rig is to be put, or in other words to the particular type of drilling to be performed. The wheel 5 being swivelly connected may be 45 swung to align with the wheels 2 and 3. 50

In the drawings, the wheels 2, 3 and 5, are shown as flanged wheels for travel over rails shown at 11, but it is to be understood that any suitable type of wheel may be employed without departing from the spirit of the present inven- 55

tion, and that the wheels are easily removable in any approved well-known manner so that the flanged wheels may be replaced by flat unflanged wheels, by wheels having rubber tires, or by any other type of wheel desired.

The carrying frame 1 has a drill-supporting frame 15 pivotally connected thereto intermediate its ends by bearing structures 16, the bolts 17 of which are loosened to permit pivotal movement of the tool-supporting frame 15 and are tightened to hold the tool-supporting frame in adjusted position.

If it is so desired, the lower cross bar 18 of the frame 15 may have a gear 19 thereon which meshes with a pinion 20 carried by the carrying frame 1. The shaft 21 on which the pinion 20 is mounted has a wrench head 22 thereon by means of which a wrench, crank handle, or the like, may be used for rotating the pinion 20 and the gear 19 to swing the tool-carrying frame 15 on its axis. As clearly shown in Figures 1 and 2 of the drawings, the tool-carrying frame 15 extends transversely of the U-shaped carrying frame 1 and parallel to the direction of travel of the portable drilling rig when the wheels 2, 3 and 5, are positioned with their axes parallel to the side members 4. When the wheels 2, 3 and 5, are adjusted with their axes transversely of or at right angles to the side members 4 then the tool-supporting frame 15 extends transversely of the direction of travel of the portable drilling rig and it has its axis transversely of the direction of travel of the frame.

The tool-supporting frame 15 comprises, besides the lower cross bar 18 the sides or standards 23 which adjustably carry the cross arm 24 on their upper ends. The cross arm 24 is connected to the standards 23 in such manner as to permit rotary movement thereof with respect to the standards 23 by means of the cones 25 formed on the ends thereof which fit in the cone-shaped recesses in the heads 26. Locking cones 27 are provided which engage in opposite or opposed cone-shaped recesses in the heads 26. The cones 25 and 27 are tightly clamped in their respective cone-shaped recesses by means of the bolt or clamping rod 28 which extends longitudinally through the cross arm 24 and through the cones 25 and 27, and the nuts 29 which are threaded thereon.

A tool-carrying unit 30 is adjustably mounted on the cross arm 24 and includes a number of elements among which is the carrying sleeve 31. The carrying sleeve 31 has a pinion 32 rotatably supported thereby which meshes with a rack 33 formed on the cross arm 24 so that rotation of the pinion 32 by the crank handle 34 will move the sleeve 31 longitudinally along the cross arm 24 and permit adjustment of the rock drill or tool 35 which is carried by the unit 30 transversely across the frame 1 for permitting various drilling positions thereon, which will be more specifically hereinafter described in connection with Figures 11 to 18 inclusive, of the drawings.

A key 36 is formed on the cross arm 24 and engages in a keyway 37 in the sleeve 31 for preventing rotation of the sleeve 31 with respect to the cross arm 24.

A slide or elongated guide 38 is attached to the sleeve 31 by the clamp structure 39 and it has rabbeted ways 40 which receive the slidable coupling 41. The slidable coupling 41 is held in adjusted positions along the slide 38 by means of the clamp or clamps 42. The clamp or clamps 42 are connected to the slide 38 by T-bolts 43 of usual approved construction and these T-bolts 43

are loosened to permit sliding of the coupling 41 along the slide 38 and tightened to hold it in position.

The coupling 41 is recessed as shown at 44 to receive the cone 45 carried by the drill-feeding mechanism 46.

The drill-feeding mechanism 46 forms a part of the drill or drilling machine 35 and in the drawings this drilling machine 35 is shown as embodying a pneumatic feed type such as illustrated in Patents #1,690,859 and #1,659,139, but it is to be understood that any approved type of drilling machine may be used in connection with the present portable drilling rig without departing from the spirit of the present invention.

The coupling 41 embodies a clamp 47 which is held in clamping engagement with the cone 45 by a T-bolt 48 which permits the clamp 47 to be swung out of clamping engagement with the cone 45. The recess 44 in the coupling 41 is circular in plan to fit or receive this cone 45 (which cone is of the usual standard type now employed in drilling machines) so that when the clamp 47 is loosened the drilling machine may be rotated on the axis of the cone 45 and consequently on an axis transversely of the pivotal axis of the tool-supporting frame 15. This is in effect pivotal movement of the drilling machine in a plane transversely of the plane of the supporting frame 15.

Anchoring members 50 are adjustably carried by supporting brackets 51 which are in turn adjustably mounted on the uprights or standards 23. These anchoring devices 50, their supporting brackets, and the manner of locking or clamping the anchoring members in adjusted positions, are of conventional type, as well as the anchoring members 52 carried by the brackets 53. The brackets 53 are attached to the carrying frame 1.

From the foregoing description taken in connection with the accompanying drawings, it will be apparent that a mobile drilling rig having a relatively great number of adjustments of position of the drilling machine 35 carried thereby, has been provided, and in Figures 11 to 18 inclusive of the drawings some of these various adjustments are illustrated.

The provision of the slide 38 which will permit longitudinal movement of the drilling machine in a plane parallel to the plane of the axis of the cross arm 24 and, when the unit 30 has been moved to the limit of its movement in either direction, will permit the drilling machine to be moved beyond the sides of the carrying frame 1 and beyond the wheels 2 or 3 so as to permit down-hole drilling close to a wall or upright surface.

In Figure 11 of the drawings the drilling machine 35 is shown in such a position. In Figure 11 the unit 30 has been moved the limit of its movement to the left along the cross arm 24 and the coupling member 41 has been moved along the slide 38 so that the drill may be placed close to the vertical wall A for down-hole drilling. The dot-and-dash lines 100 indicate various other possible positions of the drilling machine with the carrying frame 15 in position shown in this Figure 11, which is its vertical position with the wheels 2, 3, and 5 positioned with their axes transversely of the pivotal axes of the supporting frame 15. Of course only a few of the dot-and-dash lines 100 are shown in this view but it is understood that the drill 35 may be adjusted in any infinite number of positions along the cross 75

arm 24, within the limits of the slide 38 and the arm 24.

Figure 12 of the drawings illustrates a further type of adjustment which is available with the present portable drilling rig. In this Figure 12 the carrying frame 15 is in its upright position with the wheels 2, 3, and 5 positioned the same as in Figure 11, that is, the carrying frame is in a plane parallel with the direction of movement of the portable drilling rig and with its pivotal axis also parallel with the line of movement of the drilling rig. The unit 30 is illustrated in an intermediate position on the cross bar 24, and it is of course to be understood that it may be in any one of the many positions permitted along the cross arm. The dot-and-dash lines 101 illustrate how the drilling mechanism 35 may be swung on a pivot or rotated, such movement being permitted by the connection of the cone 45 with the coupling member 41. This will permit the drilling of a plurality of down-holes at various angles to the perpendicular.

Figure 13 shows a slightly different adjustment which is permitted by the present drilling rig. In this figure the wheels 2, 3 and 5, are swung so that the line of travel of the portable drilling rig will be transversely of the pivotal axis of the tool-supporting frame 15. The drill-carrying unit 30 is shown at an intermediate position along the cross arm 24 and the dot-and-dash lines 102 indicate various pivotal or rotary positions of the drilling machine 35 which may be obtained in this position through the medium of the coupling 41 and the trunnion 45. It is of course to be understood that with the wheels adjusted to the positions as shown in this Figure 13 various other adjustments of the unit 30 and the drilling machine 35 are permissible, and the unit 30 may be moved along the cross bar 24 to position the drill 35 beyond the edges or sides of the frame 1 and beyond the wheels. Figure 17 of the drawings shows in top plan such an arrangement, the dot-and-dash lines 103 indicating the possibilities of the adjustment of the drilling mechanism 35 along the cross bar 24.

Figure 14 shows the tool-carrying frame 15 in one of the infinite number of positions into which it may be moved by virtue of its pivotal connection through the medium of the bearings 16 with the carrying frame 1. In this Figure 14 the supporting frame 15 is swung on its pivotal axis so that the drilling machine 35 is positioned laterally of the carrying frame 1, and while the drilling mechanism 35 is shown in a vertical position for down-hole drilling in this figure, it is to be understood of course that it may be positioned in any one of the almost infinite number of positions possible through the medium of the slide 38, coupling 41, and the cone 45.

Figure 15 shows in top plan the drilling rig in which the adjustment of the drilling mechanism 35, as indicated therein, is similar to the adjustments shown in Figures 12 and 13. However, in Figures 12 and 13 the cross arm 24 has been rotated so that the drilling mechanism is in vertical position while in Figure 15 the cross arm 24 is positioned to hold the drilling mechanism 35 in a horizontal position, and while the tool-supporting frame 15 is shown in Figure 15 as in its vertical position it is to be understood of course that the drilling mechanism 35 may be positioned in a horizontal plane with the supporting frame 15 in any one of the infinite number of positions permissible by the pivotal mounting of the supporting frame. The dot-and-dash

lines 104 in Figure 15, illustrate adjustments of the drilling machine made by rotating or pivoting it through the medium of the rotatable connection between the cone 45 and the coupling 41.

Figure 16 is similar to Figure 14 except that it shows the drilling mechanism 35 in a horizontal position with the tool-supporting frame in a lowered angular position. This positioning of the drilling mechanism in a horizontal plane is permitted by rotation of the cross arm 24 or the rotation of the carrying slide 38 about the sleeve 31.

The rotation of the cross arm 24 also permits the positioning of the cross arm so that the crank handle 34 may always be in a position to be conveniently reached by the drill-runner.

Figure 18 shows a different positioning of the tool-supporting frame 15 so as to permit low drilling. In this figure the frame 15 is swung on its pivotal axis over the carrying frame 1, and the drilling mechanism 35 is shown positioned below the cross arm 24 instead of above as is shown in Figure 16. The dot-and-dash lines 105 merely illustrate how the drilling mechanism may be adjusted on an axis transversely of the plane of the carrying frame 1 by rotation of the cross arm 24, and it can of course be rotated or pivotally adjusted in a plane parallel to the carrying frame 1 by means of the coupling 41 and cone 45.

While these various diagrammatic Figures 11 to 18 illustrate certain positions and the dot-and-dash lines illustrate certain adjustments of the drilling mechanisms in such positions, it is to be understood that practically all of the adjustments of the drilling mechanism with respect to the supporting frame 15 are permitted in any one of the various positions shown, and also that the supporting frame 15 may be moved in innumerable other positions due to its pivotal mounting.

It will be understood that the invention is not to be limited to the specific construction or arrangement of parts shown but that they may be widely modified within the invention defined by the claims.

What is claimed is:

1. In a portable drilling rig, a carrying frame, a drill-supporting frame including side arms and a cross bar pivotally carried thereby, the cross bar of said supporting frame being rotatably carried by the side arms of the supporting frame, and means for holding said cross bar against rotary movement.

2. In a portable drilling rig, a carrying frame, a drill-supporting frame including side arms and a cross bar pivotally carried thereby, the cross bar of said supporting frame being rotatably carried by the side arms of the supporting frame, means for holding said bar against rotary movement, a sleeve mounted on said cross bar for movement longitudinally therewith, and means carried by said sleeve for connection with a drilling machine to permit swinging movement of a drilling machine on an axis transversely of the axis of rotation of the cross bar.

3. In a portable drilling rig, in combination, a drilling machine, a carrying frame, a drill-supporting frame including side arms and a cross bar pivotally carried thereby, the cross bar of said supporting frame being rotatably carried by the side arms of the drill supporting frame, means for holding said bar against rotary movement, a connecting unit mounted on said cross bar for rotary movement therewith and slidably

- movement longitudinally along the bar, said connecting unit embodying means for connecting said drilling machine thereto.
4. In a portable drilling rig, in combination, a drilling machine, a carrying frame, a drill-supporting frame pivotally carried thereby, said supporting frame including a drill-carrying cross bar rotatably carried by the drill supporting frame, means for holding said bar against rotary movement, a connecting unit mounted on said cross bar for rotary movement therewith and slidable movement longitudinally along the bar, said connecting unit embodying means for connecting said drilling machine thereto, a rack on said cross bar, and a pinion on said connecting unit and meshing with said rack for moving said unit along said cross bar.
5. In a portable drilling rig, in combination, a drilling machine, a carrying frame, a drill-supporting frame including side arms and a cross bar pivotally carried thereby, the cross bar of said supporting frame being rotatably carried by the side arms of the drill supporting frame, means for holding said bar against rotary movement, a connecting unit mounted on said cross bar for rotary movement therewith and slidable movement longitudinally along the bar, said connecting unit including an elongated guide, a drilling machine connecting member slidable in said guide whereby the drilling machine may be slidably positioned beyond the ends of said cross bar.
6. In a portable drilling rig, in combination, a drilling machine, a carrying frame, a drill-supporting frame including side arms and a cross bar pivotally carried thereby, the cross bar of said supporting frame being rotatably carried by the side arms of the drill supporting frame, means for holding said bar against rotary movement, a connecting unit mounted on said cross bar for rotary movement therewith and slidable movement longitudinally along the bar, said connecting unit including an elongated guide, a drilling machine connecting member slidable in said guide projecting beyond either end of the cross bar and beyond the carrying frame when said connecting unit is at either terminus of its adjustment along said cross bar.
7. In a portable drilling rig, in combination, a drilling machine, a carrying frame, a drill-supporting frame including side arms and a cross bar pivotally carried thereby, said cross bar of said supporting frame rotatably carried by the side arms of the frame, means for holding said bar against rotary movement, a connecting unit mounted on said cross bar for rotary movement therewith and slidable movement longitudinally along the bar, said connecting unit including an elongated guide, a drilling machine connecting member slidable in said guide and projecting beyond either end of the cross bar and beyond the carrying frame when said connecting unit is at either terminus of its adjustment along said cross bar, said connecting unit including means whereby the drilling machine may be swung on a pivotal axis transversely to the pivotal axis of said supporting frame.
8. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and independently of said cross bar and adjustable along the bar to position the drilling machine at various points across the length of the carrying frame.
9. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and adjustable along the bar to position the drilling machine at various points across the length of the carrying frame, said drill-connecting and carrying member including means whereby the drilling machine may be moved beyond the ends of said rotary cross bar.
10. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and adjustable along the bar to position the drilling machine at various points across the length of the carrying frame, said drill-connecting and carrying member including means whereby the drilling machine may be moved beyond the ends of said rotary cross bar.
11. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and adjustable along the bar to position the drilling machine at various points across the length of the carrying frame, said drill-connecting and carrying member including means whereby the drilling machine may be moved beyond the ends of said rotary cross bar, said drill connecting and carrying unit including means whereby the drilling machine may be swung about an axis transversely of the pivotal axis of the supporting frame.
12. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and adjustable along the bar to position the drilling machine at various points across the length of the carrying frame, said drill-connecting and carrying member including means whereby the drilling machine may be moved beyond the ends of said rotary cross bar, said drill connecting and carrying unit including means whereby the drilling machine may be swung about an axis transversely of the pivotal axis of the supporting frame, and means for preventing rotation of said drill-connecting and carrying member independently of said cross bar.
13. In a portable drilling rig, the combination with a rock drill, of a carrying frame, a drill-supporting frame pivotally carried by said carrying frame and adjustable to swing a drill carried thereby beyond two opposite sides of the supporting frame, said carrying frame including a cross bar rotatably connected to the frame, a drill-connecting and carrying unit rotatable with said cross bar and adjustable along the bar to position the drilling machine at various points across the length of the carrying frame, said drill-connecting and carrying member including means whereby the drilling machine may be moved beyond the ends of said rotary cross bar, said drill connecting and carrying unit including means whereby the drilling machine may be swung about an axis transversely of the pivotal axis of the supporting frame, a rack on said cross bar, a pinion carried by said drill-connecting and carrying member and meshing with said

rack for moving the drill-connecting and carrying member longitudinally along the cross bar.

13. In a portable drilling rig, the combination with a rock drill, of a carrying frame, a drill supporting frame pivotally carried by said carrying frame to normally swing on an axis transversely of the line of travel of the carrying frame and adjustable to swing a drill carried thereby beyond two opposite sides of the carrying frame, said supporting frame including a cross bar rotatably connected to the supporting frame, a drill connecting and carrying unit rotatable with said cross bar and adjustable along the bar to position the drilling machine at various points across the length of the carrying frame, said drill connecting and carrying member including means whereby the drilling machine may be moved beyond the ends of the rotary cross bar, and supporting means adjustably connected to said carrying frame whereby the supporting means may be adjusted in such manner that the supporting frame will swing on an axis transversely of the direction of travel of the carrying frame.

14. In a portable drilling rig, the combination with a rock drill, of a carrying frame, a drill

supporting frame, pivotally carried by said carrying frame to normally swing on an axis transversely of the line of travel of the carrying frame and adjustable to swing a drill carried thereby beyond two opposite sides of the carrying frame, said supporting frame including a cross bar rotatably connected to the supporting frame, a drill connecting and carrying unit rotatable with said cross bar and adjustable along the bar to position the drilling machine at various points across the length of the carrying frame, said drill connecting and carrying member including means whereby the drilling machine may be moved beyond the ends of said rotary cross bar, said drill connecting and carrying unit including means whereby the drill may be swung about an axis transversely of the pivotal axis of the supporting frame, means for preventing rotation of said drilling connecting and carrying member independently of said cross bar, and supporting wheels swivelly carried by said carrying frame whereby the wheels may be adjusted in such manner that the drill supporting frame will pivot on an axis transversely of the direction of travel of the carrying frame.

CHARLES A. HIRSCHBERG. 25
